DESIGN FOR A CLOTHESPIN

Virginia J. Jacobsen, San Diego, Calif.

Application March 22, 1946, Serial No. 128,125

Term of patent 3½ years

(Cl. D17—6)

To all whom it may concern:

Be it known that I, Virginia J. Jacobsen, a citizen of the United States of America, residing at San Diego, in the county of San Diego and State of California, have invented a new, original, and ornamental Design for a Clothespin, of which the following is a specification, reference being had to the accompanying drawing forming a part thereof.

The figure is a perspective view of a clothespin showing my new design, the opposite side presenting substantially the same appearance as the side shown.

I claim:

The ornamental design for a clothespin, substantially as shown and described.

VIRGINIA J. JACOBSEN.
